INVENTOR

Dorinda P. Le Roy

WITNESS

UNITED STATES PATENT OFFICE.

ROBERT B. PETERS, OF BROOKLYN, NEW YORK.

STEADYING DEVICE FOR ROTATABLE FLAG STANDARDS OR POLES.

Application filed October 5, 1927. Serial No. 224,183.

This invention relates primarily to steady-
ing devices for flag standards or poles, similar
to that included in petition for Letters
Patent for brackets filed with the Commis-
sioner of Patents, at Washington, D. C. on
April, 12th, 1927, Serial Number 183,129, in
behalf of Robert B. Peters, the inventor
thereof.

Another object of this invention com-
p10 prehends an annular flange member fitted with
ball or roller bearings which is rigidly se-
cured to the flag standard or pole by fasten-
ing elements.

More specifically stated this annular flange
15 member is provided with cut out portions in
the side walls extending therethrough to re-
ceive the flag halyards therein.

An additional feature of the invention
20 consists of a ring rotatably mounted within
the guide channel of the flange member, the
ends of which are appreciably spaced to per-
mit the ingress and egress of the halyards
25 within the cut out portions when the
space between the ends thereof register with
the cut out portions. The ring is provided
with arms on the outer surface diametrically
opposite each other to which are fastened
30 braces, the opposite ends of which are se-
cured to a suitable stationary structure
which holds the ring set, though the flange
member and the flag standard or pole may
rotate without the braces interfering with
35 the halyards.

With the above and other objects in view
35 the invention further consists of the follow-
ing novel features and details of construc-
tion, to be hereinafter more fully described,
illustrated in the accompanying drawings
and pointed out in the appended claim.

40 In the drawings:

Figure 1 is a side elevation of the inven-
tion,

Figure 2 is the top view thereof.

Figure 3 is a side elevation of the inven-
tion, as fitted with balls or roller bearings.

Referring to the drawings in detail,
wherein like characters of reference denote
corresponding parts, the reference character
4 indicates an annular flange member which
50 is rigidly secured to the flag standard or
pole by fastening elements 5, received

through laterally disposed ears 6, secured to
and projecting from annular flange member
4. A ring 7 is rotatably mounted within the
guide channel provided upon the outer sur-
face of the annular flange member 4, and is
in turn provided with arms 8 upon diametri-
cally opposite sides thereof, and adapted
for connection with a suitable stationary
structure to steady the pole. In the instance
of flying a flag or emblem from the standard
or pole, the halyards for the flag or emblem
would ordinarily interfere with the rotation
of the standard or pole when untangling
the flag or emblem. To overcome this diffi-
culty I provide cut out portions 10 in the
side walls of the guide channel of the annu-
lar flange member 4 which are adapted to
receive the halyards therein. A ring 7 also
rotatably mounted within the guide channel
of the flange member 4 has the ends 11 there-
of spaced an appreciable distance to permit
ingress and egress of the halyards within
the cut out portions 10, guided by a lip 12
protruding from the lower end of ring 7, 75
when the space between the ends 11 thereof
register with the cut out portions 10.

It will thus be noted that the standard
or pole may be rotated to unfurl a flag or em-
blem but the braces 9 will remain set due to
the aforementioned connection between the
annular flange member 4 and the ring 7.
The ring 7 will prevent displacement of the
halyards.

The invention is susceptible of various
85 changes in its form, proportions and minor
details of construction, and the right is here-
by reserved to make such changes as proper-
ly fall within the scope of the appended
claim.

Having described the invention, what is
claimed is:

A steadyng device for flag poles, com-
prising an annular flange member forming a
guide channel, rigidly attached to the flag
pole, said channel being fitted with ball or
roller bearings, a ring member rotatably
mounted in said guide channel, cooperating
cut out portions in the flanged member and
in the ring member, to permit ingress and
egress of the halyards when the said cut out
100 portions register, a guide lip on the lower

end of ring member; arms are provided diametrically opposite each other on the outer surface of ring member to which are fastened braces the opposite ends of which may be secured to a suitable stationary structure, holding the ring member set but permitting the flange member to revolve with the stand-

ard or pole therein, without the braces interfering with the halyards.

Signed at borough of Brooklyn, in the ¹⁰ county of Kings and State of New York, this third day of October, A. D. 1927.

ROBERT B. PETERS.
